Primary Examiner—Jeffrey Asch

(74) Attorney, Agent, or Firm—Brown Raysman Millstein Felder & Steiner LLP

(57) **CLAIM**

The ornamental design for an integrated compact disk player telephone, as shown and described.

DESCRIPTION

FIG. 1 is a perspective view of one side and the front of the device showing an operable compact disk door on the top of the device according to a first embodiment of my new design;

FIG. 2 is a front view of the first embodiment thereof; FIG. 3 is a back view of the first embodiment thereof; FIG. 4 is a side view of one side of the first embodiment thereof;

FIG. 5 is a side view of the other side of the first embodiment thereof;

FIG. 6 is a top view of the first embodiment thereof; FIG. 7 is a bottom view of the first embodiment thereof; FIG. 8 is a perspective view of one side and the front of a second embodiment thereof;

FIG. 9 is a front view of the second embodiment thereof; FIG. 10 is a back view of the second embodiment thereof; FIG. 11 is a side view of one side of the second embodiment thereof;

FIG. 12 is a side view of the other side of the second embodiment thereof;

FIG. 13 is a top view of the second embodiment thereof; and,

FIG. 14 is a bottom view of the second embodiment thereof. The broken line showings throughout the views are for illustrative purposes only and form no part of the claimed design.

The word "COBY" forming part of the drawing disclosure is a registered trademark of COBY Electronics Corp.
